UNITED STATES PATENT OFFICE.

CHARLES G. EDENHOLM, OF PHILADELPHIA, PENNSYLVANIA.

TICKET-CASE.

SPECIFICATION forming part of Letters Patent No. 551,268, dated December 10, 1895.

Application filed August 15, 1895. Serial No. 559,312. (No model.)

To all whom it may concern:

Be it known that I, CHARLES G. EDENHOLM, a subject of the King of Sweden and Norway, residing at Philadelphia, in the county of 5 Philadelphia and State of Pennsylvania, have invented certain new and useful Improvements in Ticket-Cases, of which the following is a full, clear, and exact specification.

My invention relates to a new and useful 10 ticket-case and the apparatus for use in carrying out the same, and has for its object to provide a method by the use of which persons to be served in rotation, as in barber-shops and the like, may without confusion be notified when their turn comes.

With this end in view my invention consists in certain novel apparatus and method hereinafter fully explained and then specifically designated by the claims.

20 To enable those skilled in the art to which my invention appertains to construct and use the same, I will describe it in detail, referring by number to the accompanying drawings, forming a part of this specification, and 25 in which—

Figure 1 is a front elevation of the apparatus which I use in carrying out my method; Fig. 2, a vertical section taken at the line *xx*, and Fig. 3 is a similar view taken at the line

30 *yy*. Similar numbers denote like parts in all the views of the drawings.

1 is a back or supporting-board, to which is formed or attached receptacles 2 and 3, the former of which is provided with a flanged top 4, having an opening 5, so disposed as to permit the ready withdrawal of one of a series of cards 6, contained in said receptacle, through the slot 7 in the face thereof.

40 8 is a sliding false bottom, adapted to move vertically within the receptacle 2; and 9 is a coiled spring for elevating said bottom, so that it will be seen that the cards 6 will always be held with a spring-pressure against 45 the top 4, and the topmost one may be withdrawn by the friction of one's finger upon its upper surface. These cards I prefer to number consecutively from 1 up, at their centers, upon both sides, so that whichever surface 50 be exposed their designating number may be observed.

The receptacle 3 is provided with a top 9,

having a depending lip 10, for the purpose presently explained, and in the face of this receptacle is a circular opening 11, of sufficient size to expose to view the designating numbers of the cards. The bottom and a portion of the front of the receptacle 3 are at an angle to the top and back thereof, as clearly shown in Fig. 3, so that cards placed within this receptacle and pressed against the face thereof will stand at a like angle, for the purpose hereinafter explained.

12 is a back board, fitting within the receptacle 3, and adapted to have a sliding movement and be actuated by the spring 13, so that cards 14, placed within the receptacle, will be caused to bear against the face thereof. When a card is to be placed in the receptacle 3, it is inserted through the slot 15, and forced 70 down below the edge of the lip 10, when its upper portion will spring in line with the front of the receptacle, causing its upper edge to pass back of said lip, whereby its withdrawal is prevented.

75 16 is a cut-away portion in the front of the receptacle 3, of sufficient size to allow the finger of a person to pass therein when inserting one of the cards 14 within said receptacle.

The tops 4 and 9 of the receptacles 2 and 3, respectively, may be bolted upon their respective receptacles, so as to facilitate the renewal or removal of the cards from said receptacles.

80 From the foregoing description the application and operation of my device will be obviously as follows: The device is placed in a prominent and convenient location in the room where customers are served, and upon the entry of each person he is required to 85 withdraw one of the cards from the receptacle 2, and retain said card during the period that he is required to wait while others are being served, and when the designating number of the card he holds is called he is required to 90 insert said card within the receptacle 3, when its number will be exposed to the view of not only the customers then waiting, but also to the person or persons serving said customers, so that when there is occasion to serve another customer the number next above the one exposed in the receptacle 3 will be called, and the person holding said number will be 95 made aware that it is his turn to be served.

Thus there can be no confusion or mistake as to whose turn is next.

Having thus fully described my invention, what I claim as new and useful is—

- 5 1. An article of manufacture consisting of a receptacle having a spring pressed partition, and an opening 11, slot 5, cut away portion 16 and lip 10, as and for the purpose described.
- 10 2. An article of manufacture consisting of a base, a receptacle arranged thereon having a spring pressed false bottom, flanged top 5 and slot 7, a second receptacle 3 arranged on

the base at the side of the receptacle 2 and having a spring pressed partition, opening 11, slot 5, cut-away portion 16 and lip 10 all arranged to operate, as and for the purpose described.

In testimony whereof I have hereunto affixed my signature in the presence of two subscribing witnesses.

CHARLES G. EDENHOLM.
